DESIGN FOR A PLACE CARD HOLDER

Grant Wortman, Chicago, Ill.

Application July 21, 1945, Serial No. 120,864

Term of patent 7 years

(Cl. D59—2)

To all whom it may concern:

Be it known that I, Grant Wortman, a citizen of the United States, residing at Chicago, in the county of Cook and State of Illinois, have invented a new, original, and ornamental Design for Place Card Holders, of which the following is a specification, reference being had to the accompanying drawing, forming part thereof.

Fig. 1 is a frontal perspective view of a place card holder, showing my new design; and
Fig. 2 is a vertical section at a medial point.

I claim:

The ornamental design for a place card holder, as shown.

GRANT WORTMAN.
